CLAIM

I claim the ornamental design of a bench, as shown and described herein.

DESCRIPTION

Portions of the disclosure of this patent document contain material that is subject to copyright protection. The copyright owner has no objection to the facsimile reproduction by anyone of the patent document or the patent disclosure as it appears in the Patent and Trademark Office file or records, but otherwise reserves all copyright rights whatsoever.

FIG. 1 is a front view of a bench according to the new design.
FIG. 2 is a front perspective view of the bench according to the new design.

FIG. 3 is a left side view of the bench according to the new design. The right side is the same; and,

FIG. 4 is a rear view of the bench according to the new design.

1 Claim, 4 Drawing Sheets
